(57) **CLAIM**

The ornamental design for a ladder wheel pair, as shown and described.

DESCRIPTION

FIG. 1 is a perspective view of a ladder wheel pair as coupled to a lower portion of a ladder showing our new design;

FIG. 2 is a front view of one of the ladder wheels shown in FIG. 1;

FIG. 3 is a bottom view of the ladder wheel shown in FIG. 2;

FIG. 4 is a bottom-right-front perspective view of the ladder wheel shown in FIG. 2;

FIG. 5 is a top-left-front perspective view of the ladder wheel shown in FIG. 2; and,

FIG. 6 is an enlarged perspective view shown from the opposite side of the ladder wheel pair shown in FIG. 1.
